VEHICLE WINDOW REGULATOR

Burton S. Floraday, Toledo, Ohio, assignor to
 Marvel Equipment Corporation, Detroit, Mich.,
 a corporation of Michigan

Application October 26, 1944, Serial No. 560,372

2 Claims. (Cl. 268—126)

1

This invention relates to vehicle window regulators but more particularly to cross arm regulators which are employed for actuating window panels of automobiles.

An object is to produce a regulator of the above type in which the operating unit is spaced substantially from the regulator mechanism but is connected thereto in such manner that the effort required for operation is substantially reduced.

Another object is to provide a cross arm window regulator with bell crank means actuated by the remote control unit, the parts being so constructed and arranged that adjustment may be effected to accommodate the mechanism to various handle locations in accordance with the width or configuration of the vehicle door or body structure.

A further object is to provide new and improved means for actuating a cross arm window regulator from a remote location.

Other objects and advantages will hereinafter appear and for purposes of illustration but not of limitation, embodiments of the invention are shown in the accompanying drawings, in which

Figure 1 is an inside fragmentary side elevational view of an automobile door partly broken away, illustrating a window regulator in which the present invention is embodied;

Figure 2 is a fragmentary transverse sectional view of the mechanism shown in Figure 1, taken substantially on line 2—2 of Figure 1; and

Figure 3 is a perspective view of a portion of the invention.

The present invention embraces, in particular, adjusting means for window regulating mechanism and is especially applicable where a window regulator of a substantially standard design is to be installed in the window well of an automobile door. Such apparatus may be employed in either front or rear doors with equal facility. Minor adjustments to the mounting members are not infrequently necessary during installation due to inaccuracy or irregularity of the door structures. Furthermore, variously styled doors may provide for the window operating handle in different positions or relation with respect to the location of the regulator. In Figures 1, 2 and 3 of the drawings, I have shown an embodiment of the invention, a description of which follows.

An automobile door D (Figure 1) which may be, for purposes of illustration, a front door of standard construction, includes outside and inside panels 10 and 11 respectively, enclosing a well 12 into which the usual window regulating mechanism is disposed. A window panel 13 arranged to slide vertically into the well in guide channels 14

2

is under the control of a window regulator indicated generally at 15. The guides 14 extend into the well to support the window 13 when it is lowered and concealed from view by the door panels. In this lowered position, the regulator 15 assumes the broken line position 15a.

The window panel 13 has secured to its lower edge the usual channel bar 17 to which are secured depending laterally spaced horizontal guide members or retainers 18 adapted slidably to receive studs or rollers 19 carried by the arms of the regulator 15. The crossed regulator arms designated respectively as a driving arm 20 and a guide or balance arm 21 are pivoted together medially of their length at 22 and are arranged to swing through an arc of substantially 90 degrees as the window is lowered into the well 12 to the concealed position.

The arm 20 is mounted at the end opposite its stud 19 for swinging movement about a fixed stud 24 fixed to a mounting plate 25, which is adapted to be secured to the inside door panel, as shown in Figures 1 and 2. The arm 21 is provided on its end opposite the stud 19 with a stud 19a adapted to slide within a horizontal slot 19b formed in the mounting plate and extending in a direction parallel to a plane passing through the fixed stud 24.

Driving means for operating the regulator comprises generally a relatively short lever arm 30, to be described in detail presently, connected at one end to the driving arm 20, inclining upwardly and laterally therefrom, and having its other end connected by a link 31 to a gear sector 32 pivoted on a mounting plate 33. The sector 32 and associated parts form a substantially unitary assembly for attachment to the inner door panel 11, which further includes a drive pinion 34 for driving the gear 32 mounted on a driving shaft 35 supported within a conventional friction clutch device 36 also secured to the mounting plate 33. A conventional crank handle shown in broken lines may be attached to the shaft 35 for actuating the regulator mechanism from the inside of the door, as will be readily understood.

The mechanism thus far described represents a construction, which is adapted to be assembled as a unit into a previously formed door. At times, doors of different manufacture often provided for locating the crank handle in different positions with respect to the regulator mounting plate 25. This may require for instance, reducing or enlarging the length of the link 31 from that shown in Figure 1 and also altering the angular relation of the lever 30 with the arm 20 so that proper leverage at all times can be main-

tained. This is accomplished in the present invention by forming the lever 30 separately from the arm 20, as shown in Figure 3, and, when the desired relation is determined, securing the two members together by means of rivets 31. Holes 38 for the rivets in the lever 30 may be formed prior to assembly with the arm 20 and holes 39 in the arm 20 drilled to assure proper alignment of the members. To enable adjustment of the angular relation of the arm 20 and lever 30, additional rivet holes 39a (only one of which is shown) may be provided in the arm 20. In this manner, the lever 30 may be initially adjusted to compensate for different length links 31.

It is to be understood that numerous changes in details of construction, arrangement and operation may be effected without departing from the spirit of the invention especially as defined in the appended claims.

What I claim is:

1. Automobile window regulator mechanism comprising a swinging regulator arm adapted operatively to engage at its outer end an edge portion of a window panel for actuation thereof, a pivotal mounting for the inner end of said arm, separate actuating means disposed at one side of the plane of window movement, an operative connection between said actuating means and said regulator arm, said connection including a horizontally disposed link and a relatively short arm to the outer end of which said link is pivoted, said short arm extending at substantially right angles to the inner end of said swinging arm and being

15

initially adjustable angularly relative thereto during installation of the regulator mechanism, and means for securing said short arm rigidly to the end portion of said swinging arm.

5 2. Automobile window regulator mechanism as claimed in claim 1, comprising enlargements on the adjacent ends of the swinging regulator arm and the short arm, said enlargements having apertures for selective registration and fasteners insertable through the registering apertures enabling rigid securing of the parts after proper angular adjustment of the short arm has been effected.
